(57) CLAIM

The ornamental design for probe style radiometer, as shown and described.

DESCRIPTION

The design patent application is related to U.S. patent application Ser. No. 09/725,771.

FIG. 1 is a perspective view of the probe style radiometer;

FIG. 2 is a top view of the probe style radiometer;

FIG. 3 is a right side view of the probe style radiometer;

FIG. 4 is a bottom side view of the probe style radiometer;

FIG. 5 is left side view of the probe style radiometer;

FIG. 6 is front view of the probe style radiometer; and,

FIG. 7 is a rear view of the probe style radiometer.
